UNITED STATES PATENT OFFICE.

CHARLES B. WANAMAKER, OF INDIANAPOLIS, INDIANA, ASSIGNOR TO LEEDY MANUFACTURING COMPANY, OF INDIANAPOLIS, INDIANA, A CORPORATION OF INDIANA.

TENSIONING DEVICE FOR TYMPANA.

1,269,984.

Specification of Letters Patent. Patented June 18, 1918.

Application filed December 9, 1916. Serial No. 136,120.

To all whom it may concern:

Be it known that I, CHARLES B. WANAMAKER, a citizen of the United States, residing at Indianapolis, in the county of Marion and State of Indiana, have invented a new and useful Tensioning Device for Tympana, of which the following is a specification.

The object of my invention is to provide an improved tensioning device for tympana, wherein the weight of the parts is reduced to a considerable degree below that of standard constructions of the present time, and wherein the parts are so associated as to avoid unsightly extensions.

At the present time, the standard construction of tensioning devices is one in which the threaded portion of the tensioning screw passes through a ball nut, carried in a bracket riveted to the main body of the tympanum, and this construction, in order that the parts have sufficient strength, has necessarily involved considerable weight which is eliminated by my present construction. The elimination of unnecessary weight in instruments of this character results in a decided improvement in tone quality.

The accompanying drawings illustrate my invention. Figure 1 is a perspective view of a tympanum equipped with my improved tensioning device. Fig. 2 a full sized side elevation of one of the tensioning devices; Fig. 3 a section on line 3—3 of Fig. 2; Fig. 4 a section on line 4—4 of Fig. 2; and Fig. 5 a section on line 5—5 of Fig. 2.

In the drawings, 10 indicates the main body of the tympanum, 11 the head ring, 12 the head, and 13 the tensioning ring, preferably formed of angle iron. Secured to the ring 13 at various points are clips 14 of sheet metal, each embracing a thimble 15. Each clip 14 may be formed of comparatively light sheet metal and riveted to the ring 13, the strip having a width sufficient to lie snugly between the end flanges 16 of thimble 15. Such an arrangement is, for a given strength, considerably lighter than the perforated-lug casting commonly used. The upper end of thimble 15 is provided with a ball-seat 17, adapted to receive the ball segment 18, which is provided with a perforation 19. The upper flat face of the ball segment 18 forms a seat for the lower end of the handle nut 20, which is, externally, of standard form having a vertical

shank 21 and oppositely extending arms 22, 55 22 at the upper end. The shank 21 is necessarily of sufficient extent to provide adequate finger space beneath arms 22 and ring 13. Heretofore this shank has been solid, and has carried a downwardly extended threaded shank, said shank passing through an apertured boss, carried by ring 13, and then through a ball nut, carried by a bracket attached to the main body 10, so that the threaded portion of the shank extended 60 65 through, and was exposed beneath, the ball nut.

In my present construction, shank 21 is made hollow, as indicated at 24, and is provided with threads 25, adapted to receive 70 the threaded portion 26 of a screw 27, provided with a ball head 28. The head 28 is supported in a downwardly presented pocket 31, the upper portion of which is semi-spheroidal and perforated at 32 to permit 75 the passage of screw 27. The pocket 31 is preferably formed by proper shaping of sheet metal, which is also bent to form an integral bracket having a laterally projecting web, 33, composed of two thicknesses of 80 the material, and oppositely extending foot pieces 34 which may be attached to main body 10 by rivets 35. By using sheet metal for this pocket bracket, a very substantial piece, capable of withstanding the great 85 pressures to which it is necessarily subjected, can be produced at a minimum weight. Turning of head 28 about the axis of screw 27 is prevented by transversely slotting the head, as indicated at 36, and passing a pin 90 37 therethrough, the said pin lying in a cylindrical pocket 38, formed in the adjacent faces of the web pieces 33. As will be seen from Figs. 3 and 5, pin 37 is retained in place when the bracket is riveted to the 95 main body, and is not exposed at the outer end of the bracket.

The threaded portion 26 is no longer than that which has heretofore been required for the total vertical adjustment of ring 11, and the structure as a whole is, therefore, lighter than the preceding structures by the amount of material removed from the interior of shank 21.

Head 28, being integral with screw 27, 105 may, of course, be of considerably less diameter than would be required by the use of a ball nut through which the threaded portion

of the tensioning screw is passed, and, consequently, my device is still further lighter than a device of the ball nut type.

It will also be noted that in all positions 5 of adjustment, the threaded portion of screw 27 is entirely hidden from view and that there is nothing projecting below the bracket or pocket 31. As a consequence, my device is much more slight and thus unlikely to 10 catch the clothing of persons passing the same, than the present standard construction.

I claim as my invention:

1. A tensioning device for tympana, comprising a supporting thimble carried by the head ring, a hollow threaded hand nut supported upon the thimble, an upwardly presented threaded shank passed through the thimble and into the nut, and a support 15

carried by the main body of the tympanum 20 and resisting upward displacement of said shank.

2. A tensioning device for tympana, comprising a supporting thimble carried by the head ring, a hollow threaded hand nut supported upon the thimble, an upwardly presented threaded shank passed through the thimble and into the nut and provided at its lower end with a ball head, and a support 25 carried by the main body of the tympanum 30 and provided with a ball pocket receiving the ball head of the threaded shank and resisting upward displacement of said shank.

In witness whereof, I have hereunto set my hand at Indianapolis, Indiana, this 5th day of December, A. D. one thousand nine 35 hundred and sixteen.

CHARLES B. WANAMAKER.
